CLAIM

The ornamental design for an air freshener device, as shown and described.

DESCRIPTION

FIG. 1 is a top perspective view of a first embodiment of our air freshener device;

FIG. 2 is a bottom perspective view of said first embodiment thereof;

FIG. 3 is an elevation view of the rear of said first embodiment thereof;

FIG. 4 is an elevation view of the front of said first embodiment thereof;

FIG. 5 is an elevation view of the right side of said first embodiment thereof;

FIG. 6 is a plan view of the top of said first embodiment thereof;

FIG. 7 is a plan view of the bottom of said first embodiment thereof;

FIG. 8 is a top perspective view of a second embodiment of our air freshener device;

FIG. 9 is a bottom perspective view of said second embodiment thereof;

FIG. 10 is an elevation view of the rear of said second embodiment thereof;

FIG. 11 is an elevation view of the front of said second embodiment thereof;

FIG. 12 is an elevation view of the right side of said second embodiment thereof;

FIG. 13 is a plan view of the top of said second embodiment thereof; and,

FIG. 14 is a plan view of the bottom of said second embodiment thereof.

The broken lines shown in the drawings are for illustrative purposes only and form no part of the claimed design.
